UNITED STATES PATENT OFFICE.

JOHN T. REED, OF ST. JOHN, NEW BRUNSWICK, CANADA.

DESIGN FOR A PHOTOGRAPH-STAND.

Specification forming part of Design No. **11,264**, dated June 24, 1879; application filed May 9, 1879.
[Term of patent 3½ years.]

To all whom it may concern:

Be it known that I, JOHN T. REED, of St. John, New Brunswick, Canada, have invented a new Design for Photograph-Stands, of which the following is a specification.

The design is represented in the accompanying drawing by a perspective view of the stand.

A A are the side frames or supports of the holder, connected by cross bars or rods b, and slotted at c to receive the photograph. The side frames, A, correspond in size and shape. They are formed with plain flat sides and curved edges, terminating at each end in semicircular knobs e and a raised central portion, d, of semicircular form. The bars b are round.

Having thus described my invention, what I claim as new, and desire to secure by Letters Patent, is—

A design for a photograph-stand, which consists of side frames, A, formed with flat sides, curved edges, terminating at each end in semicircular knobs e, central raised portion, d, of semicircular form, and central slot, c, connected by rods or bars b, as shown and described.

JOHN TWELLS REED.
